DESIGN FOR A WATCHCASE

George Moses, Savanna, Ill.

Application November 17, 1944, Serial No. 116,385

Term of patent 14 years

(Cl. D42—8)

To all whom it may concern:

Be it known that I, George Moses, a citizen of the United States, residing at the Proving Ground, Savanna, in the county of Carroll, State of Illinois, have invented a new, original, and ornamental Design for a Watchcase, of which the following is a specification, reference being made to the accompanying drawing, forming a part thereof.

In the drawing,

Fig. 1 is a front elevational view of a watchcase, showing my new design;

Fig. 2 is a rear elevational view thereof;
Fig. 3 is an edge view thereof as seen from the right side, as shown in Fig. 1;

Fig. 4 is a plan view thereof; and

Fig. 5 is a fragmentary sectional view showing the bead around the edge of the case as it would appear in a section along a plane indicated by the line 5—5, Fig. 1.

I claim:

The ornamental design for a watchcase, substantially as shown.

GEORGE MOSES.
